UNITED STATES PATENT OFFICE

2,184,484

SYSTEM FOR VENTILATING ROOMS

Gustav Bojner, Stockholm, Sweden

Application June 28, 1937, Serial No. 150,841
In Sweden November 23, 1936

1 Claim. (Cl. 98—33)

A major problem in the art of ventilation is to supply and/or to remove sufficiently great quantities of air without producing any uncomfortable draft. It is a well-known matter of fact that the inconvenience of draft cannot be removed by preheating the air supplied. The demand for a frequent change of air was heretofore incompatible with the condition of freeness of draft, and more or less unsatisfactory compromises were the result of these two contradictory facts.

The chief purpose of this invention is to remove such drawbacks and to render it possible to supply to and/or to remove from rooms and more or less confined spaces or chambers great quantities of air without causing any uncomfortable and, to some persons, even dangerous draft.

Another purpose of this invention is to supply the air to and/or to remove it from chambers or rooms, in currents whose directions and possibly also intensity vary continuously or intermittently at rather short intervals of time.

Another object of this invention is to change the direction of flow in the air inlets and/or air outlets periodically at such short intervals that no draft will be felt by persons in the room ventilated.

Another object of this invention is to supply the air pulsationally to the room or other chamber under ventilation.

Other objects of this invention will be evident from the following specification and claim.

It has now been found that the uncomfortable or unfavorable action of draft, that is of flowing air, is felt and established only if the air flows continuously in the same direction or forms whirls or vortices either of a substantially stationary character (whirlpools) or moving substantially in the same direction. Of course, excepting those high velocities of air, which cannot practically be used in the ventilation of rooms, in which people are present, it has now been established that physiologically air currents have no unfavorable or unpleasant action upon the human body, if they do not blow continuously or for certain fixed minimum periods in the same direction. These minimum periods are somewhat different for different individuals, but may be determined rather precisely under the conditions and circumstances in every case. The frequency used in changing the direction of the air currents in accordance with this invention, when intermittent operation is used, is to be so high that each period in either direction is well below such minimum value, which is thus a max-

imum value from the point of view of the present invention. It is to be observed that in every individual case the length of the periods of reversal must be determined with regard to the velocity of the air and to the shape of the chamber to be ventilated, but too short periods cannot be used. As a convenient average, 1 to 5 reversals per minute may be mentioned.

Various embodiments of the means for carrying this invention into effect are, of course, possible. Some examples are shown in the annexed drawing, in which:

Fig. 1 shows a vertical section on the line I—I in Fig. 2 through a room ventilated in accordance with this invention.

Fig. 2 is a horizontal section on the line II—II in Fig. 1.

Fig. 3 shows a horizontal section through a room, such as a theater, having a system of ventilation in accordance with another embodiment 20 of this invention.

Fig. 4 shows a horizontal section illustrating still another embodiment, having a single inlet and double outlets.

Fig. 5 is a vertical section on the line V—V in Fig. 6 through a plant embodying another modification of this invention.

Fig. 6 is a horizontal section on the line VI—VI in Fig. 5.

Referring now to Figs. 1 and 2 of the drawing, 30 1 indicates a room to be ventilated, such as a theater, a cinema, a workshop or the like. In this room two tubes or channels 2, 3 are arranged having perforated or slotted walls. A supply pipe 4 for fresh air and a discharge pipe 35 5 for consumed or foul air have a common rotary valve or damper 6 at the junction point of the tubes 2, 3. An electric motor 7 is operatively connected with the valve 6 by a belt 8 or the like. The fresh air is pressed into the inlet 40 4 by a ventilator or fan 9.

In operation, the motor 7 is run intermittently to move the damper 6 from the position shown by a full line in Fig. 2 to that shown by a dotted line, and vice versa. In the position shown by 45 a full line in Fig. 2 the damper 6 admits the fresh air from the pipe 4 to the pipe 2, while the foul air is let out through the pipe 3 then in communication with the discharge pipe 5. Generally, the increased pressure of the incoming air 50 suffices for driving out the foul air through the discharge pipe 5 and it is, as a rule, not necessary to connect the pipe 5 with an exhaust fan or a chimney having natural draft. When the damper 6 is moved to its opposite position, as 55

- shown by a dotted line in Fig. 2, the fresh air flows into the room through the pipe 3 and the foul air is discharged through the pipe 2. The motion of the damper 6 from one end position to the other should be rapid, to reduce the loss of fresh air by direct flow from pipe 4 to pipe 5. Preferably, the motion of the damper 6 from one end position to the other should be effected in a few seconds or in even less than a second. It is necessary that the damper is reversed at such short intervals (generally from 1 to 5 reversals per minute) that no appreciable draft is felt in the room 1, at least in those parts thereof in which persons are generally present.
- 15 In Fig. 3 the room 1a to be ventilated has a gallery or balcony 10. The supply pipe 4a for fresh air is connected with an inlet pipe 2a above said gallery and an inlet pipe 3a below the same. A damper 6a, which is intermittently or continuously reversed or rotated, opens a communication from pipe 4a to either or both of the pipes 2a, 3a. By preference, the damper 6a is rotated slowly. It is evident that the directions of the currents of air in the room 1a are varied as a result of the motion of the damper 6a. The foul air escapes through a discharge pipe 5a.
- The same effect is attained, if the direction of flow in the pipe 4a is changed, that is, if 4a is a pipe for sucking air from the room 1a.
- 30 In the embodiment shown in Fig. 4, the room 1b has an air supply pipe 4b connected with a distributing pipe 11 with slots or perforations for letting in the air into the room. Two outlet pipes 12 and 13 are shown which are connected to a common discharge pipe 15 by a valve or damper 14, which is rotated or reversed continuously or periodically by an electric motor 16 through a reducing gear 17. A slow rotation of the damper 14 is preferred. It is evident that 40 the currents of air from the distributor 11 will

flow alternately to the outlets 12 and 13, and in some moments to both of them. Thus, the currents of air in the room will incessantly change their direction, thus preventing the uncomfortable or unfavorable physiological action of draft. 5

In Figs. 5 and 6, the room has two slotted or perforated intakes 18, 19 for fresh air, arranged below the ceiling. At the floor there are two outlet channels 20, 21 extending along two opposite walls of the room. A common inlet tube 22 for compressed fresh air is connected with the intakes 18, 19 by a valve or damper 23. Analogously, a discharge pipe 24 for the foul air is connected with the two outlet pipes 20, 21 by a valve 25. The two valves 23, 25 are rotated 15 or reversed in unison by an electric motor 26 via a speed-reducing gear 27. However, the valves 23, 25 have an angular displacement of 90°, that is the valve 23 is 90° in advance of or behind the valve 25. The main positions of the valves 20 are shown in full lines and dotted lines, respectively. The directions of flow for the full line position are shown by full arrows, and the directions of flow corresponding to the dotted line position of the valves are indicated by dotted 25 arrows.

The air supplied may in all cases be conditioned, that is, its temperature or percentage of moisture, or both, may be regulated to the desired values, by well-known means. 30

What I claim is:

A system for airing rooms and other chambers having an air inlet and an air outlet opening, comprising automatic means for reversing the directions of flow of the currents of air in said inlet and outlet openings at such short intervals of time that the draft in said chamber is substantially imperceptible. 35
